UNITED STATES PATENT OFFICE

95,936

DESIGN FOR AN ALPHABET FOR FORMING MONOGRAMS OR THE LIKE

Leo K. Stupell, New York, N. Y.

Application April 1, 1935, Serial No. 56,162

Term of patent 14 years

To all whom it may concern:

Be it known that I, Leo K. Stupell, a citizen of the United States and resident of New York, in the county of New York and State of New York, have invented a new, original, and ornamental Design for Alphabet for Forming Monograms or the like, of which the following is a specification, reference being had to the accompanying drawing, forming part thereof.

In the drawing:

Fig. 1 is a plan view of an alphabet for forming monograms or the like. The letters of the alphabet are formed from metal or other material.

Fig. 2 is a perspective view of the letter A of the alphabet shown in Fig. 1.

The letters have a curved upper surface and bevelled edges as illustrated.

The letters M and W are alike.

The letters Q and X are omitted.

I claim:

The ornamental design for an alphabet for forming monograms or the like, substantially as shown and described.

Signed at Providence, in the county of Providence and State of Rhode Island, this 29th day of March A. D. 1935.

LEO K. STUPELL.
